UNITED STATES PATENT OFFICE.

SAMUEL McDONALD, OF BRADDOCK, PENNSYLVANIA.

PROCESS OF MANUFACTURING BESSEMER STEEL.

SPECIFICATION forming part of Letters Patent No. 287,842, dated November 6, 1883.

Application filed July 28, 1883. (No specimens.)

To all whom it may concern:

Be it known that I, SAMUEL McDONALD, a citizen of the United States, residing at Brad- dock, in the county of Allegheny and State of Pennsylvania, have invented certain new and useful Improvements in Process of Manufac- turing Bessemer Steel, of which the following is a specification.

My invention has relation to improvements in the Bessemer process of making steel; and the object of my improved process is to reduce the cost of manufacture, as well as lessen the time of production, and produce a super- 10 ior article of steel by the use of the ordinary forms of converters; and to these ends the process consists in dividing the air-blast, so as to force a portion of it through the charge and a portion into the converter without passing through said charge, as will be hereinafter 15 more fully described.

In carrying out my improved process the ordinary form of converter may be used, and the charge introduced in the usual manner while the converter is in the horizontal position. The blast is then turned on, and the converter gradually tilted to about, say, thirty or forty degrees from its former position. This allows the charge to partially cover the tuyere in the bottom of the converter, and a 20 portion of the blast to escape through the body of the charge, and the remaining portion enters the converter above the charge. That portion of the blast which passes through the charge furnishes its oxygen to the carbon of the metal, forming carbonic-oxide gas, which 25 escapes to the surface. There it combines with the oxygen of the blast admitted above said charge, and produces an intense heat, which raises the temperature of the charge to 30 a degree required to produce a pure article of steel.

It will readily be seen that the utmost im- 35 portance is attached to the degree of inclina- tion of the converter, so that the proper pro- portions of air may be admitted above and 40 through the charge to accomplish the best re- sult; and as these proportions vary with the composition of the different charges, skill and experience are required in determining said 45 inclination to attain these ends.

I have very successfully carried out my pro- 50 cess by raising the converter to a vertical po- sition after it has been charged and the blast

applied, and then gradually lowering it until the proper proportion of air was admitted 55 above the blast to produce a perfect combus- tion in the converter, whereby the degree of heat may be regulated, as above set forth.

While I have described a way to carry out my process, I do not wish to limit myself to 60 any particular manner of carrying out said invention, as it will be apparent that any sys- tem by which the blast may be admitted sim- 65 ultaneously through and above the charge will accomplish said result.

I have found it necessary at times to vary the proportions of the divided blast in the same charge, for if, upon observation, the charge should be heating too much, the con- 70 verter must be brought nearer a vertical posi- 75 tion. This cuts off a portion of the direct blast and lessens the supply of oxygen. Con-sequently the temperature lowers, as required. If, on the other hand, the charge should be cooling, the converter is tilted nearer a hori- 80 zontal position. This increases the direct blast, and a greater amount of oxygen is supplied, and a greater degree of heat obtained in the converter.

I am aware that substances rich in oxygen 85 have been blown into molten metal, and an air-blast supplied above the same; but I use air alone and regulate its admission in proper proportions by varying the degree of inclina- 85 tion of the converter.

Having thus fully described my improved process, what I claim as new and useful, and desire to secure by Letters Patent of the United States, is—

1. The improvement in the process of man- 90ufacturing Bessemer steel, which consists in si- multaneously admitting the air-blast through 95 and above the charge, as set forth.

2. The improvement in the process of man- 90ufacturing Bessemer steel, which consists in si- multaneously admitting the air-blast through 95 and above the charge and varying the relative proportions of said blast, as and for the pur- poses set forth.

In testimony whereof I affix my signature in 100 presence of two witnesses.

SAMUEL McDONALD.

Witnesses:

JOS. WALTERMEYER,
H. J. ENNIS.
